Inventor:

T. W. Bürger

United States Patent Office.

T. W. BURGER, OF NEW YORK, N. Y.

Design No. 3,569, dated July 6, 1869.

DESIGN FOR THE TOP OF AN OIL-CAN.

The Schedule referred to in these Letters Patent and making part of the same.

To all whom it may concern:

Be it known that I, T. W. BURGER, of New York city, in the county and State of New York, have invented a new and improved Design for Oil-Cans; and I do hereby declare that the following is a full, clear, and exact description thereof, which will enable others skilled in the art to make and use the same, reference being had to the accompanying drawings, forming part of this specification, in which—

Figure 1 is a side view of the upper part of my improved can.

Figure 2 is a top view of the same.

Similar letters of reference indicate corresponding parts.

My invention has for its object to furnish an improved design for a can, to contain essential oils and other liquid substances; and

It consists in the design hereinafter more fully described.

A represents the body of the can, which is cylindrical in form, and

B is the top of the can, which is convex in its general form.

The central part of the top, B, is slightly convex, and is surrounded with a slight beading, b'.

The outer part of the top, B, surrounding the beading b', is made upon a steeper curve, as clearly shown in the drawings.

C is the nozzle, through which the liquid is introduced into and removed from the can, and which passes through the top, B, close to the edge of said top, as shown in figs. 1 and 2.

Having thus described my invention,

What I claim as new, and desire to secure by Letters Patent, is—

The design for an oil-can herein set forth.

The above specification of my invention signed by me, this 8th day of June, 1869.

T. W. BURGER.
